UNITED STATES PATENT OFFICE.

MARCUS A. JUAREZ, OF OXNARD, CALIFORNIA.

HORSE-DETACHER.

1,134,134.

Specification of Letters Patent. Patented Apr. 6, 1915.

Application filed November 18, 1913. Serial No. 801,661.

To all whom it may concern:

Be it known that I, MARCUS A. JUAREZ, citizen of the United States, residing at Oxnard, in the county of Ventura and State of California, have invented certain new and useful Improvements in Horse-Detachers, of which the following is a specification.

This invention relates to improvements in devices operative from the driver's seat for releasing horses in event of their running away or becoming otherwise unmanageable, and has for one of its objects to improve the construction and increase the efficiency and utility of devices of this character.

Another object of the invention is to provide a simply constructed device which may be adapted to a single horse or two-horse vehicle without material structural change either in the vehicle or in the attachment. With these and other objects in view the invention consists in certain novel features of construction as hereinafter shown and described and then specifically pointed out in the claims, and in the drawings illustrative of the preferred embodiment of the invention.

Figure 1 is a plan view of a portion of a pair of thills and the cross bar and swingletree with a portion of the improved device applied. Fig. 2 is an enlarged sectional detail on the line 2—2 of Fig. 1. Fig. 3 is a rear elevation of the parts shown in Fig. 2. Fig. 4 is a plan view of the parts shown in Figs. 2 and 3. Fig. 5 is a perspective view of one of the guide plates. Fig. 6 are perspective views of the slidable whiffletree support.

Corresponding and like parts are referred to in the following description and indicated in all the views of the drawings by the same reference characters.

A portion of the improved device is arranged to enable the swingletree to be released from the driver's seat, and when employed upon a single-horse vehicle the swingletree releasing mechanism will be applied to the cross bar of the thills, and when employed upon a two-horse vehicle the swingletree releasing mechanism will be employed upon the doubletree, but the releasing mechanism is substantially the same for both two-horse and one-horse vehicles, the slight differences necessary to adapt the device for either not constituting a departure from the principle of the invention.

The thills are represented conventionally

at 10—11 and the connecting cross bar at 12. Located upon the cross bar and spaced slightly from its center is a guide device comprising an upper bearing plate 13 having longitudinal slots 14 opening through the forward and rear edges and with pockets 15 depending from the plate and communicating respectively with the slots. At one end each pocket is continued forwardly to form sockets 15¹ at one side of each slot and in advance of the plate 13 and facing inwardly, as shown.

The body of the member 12 is provided with recesses for receiving the depending pocket portions 15, and the member 12 is slightly thickened centrally, as shown, to compensate for the material cut away to produce the sockets and thus not reduce the strength of the cross bar. Slidably bearing upon the upper face of the member 13 is another plate 16 having depending lugs 17 which engage in the slots 14 and with outwardly directed lateral studs 18 which engage within the pockets 14 and extend into position to engage in the sockets 15¹ when the plate 16 is moved into its forward position, as hereafter explained. Projecting upwardly from the plate 16 is a holding stud 19 having its forward face curved rearwardly, as represented at 20. The rearward edge of the plate 16 when in operative position projects slightly beyond the member 12 and is provided with a guide aperture 21, the guide aperture being thus located normally rearwardly of the member 12.

The slots 14 are reduced at the rear of the member 13 whereby overhanging portions 15² are produced, and the member 16 is provided with clips 15³, preferably integral therewith, which engage beneath the overhanging portions, and thus prevent upward movement of the member 16 so long as the clips are in engagement with the overhanging portions, but which will not prevent the release of the member 16 when the clips pass into the wider forward portions of the slots 14.

Connected to the member 12, preferably to its lower face, is a bracket including a base portion 22 and an upwardly directed standard 23, the latter being spaced rearwardly of the member 12 and extending for a considerable distance above the upper line of the same. Pivoted at 24 to the standard 23 at its upper end is a releasing lever 25, the forward end of the lever extending be-

yond the line of the stud 19 and provided with a depending lug 26 which engages the upper end of the stud 19 when the lever 25 is in its closed or depressed position. The 5 whiffletree is represented conventionally at 27, and extends between the plate 13 and the forward end of the lever 25, and is apertured to receive the stud 19 and the depending lugs 26, as shown in Fig. 2. A spring 10 28 is connected at one end to the lever 25 and connected to the portion 22 of the bracket by a threaded rod 28¹ and wing nut 28², and exerts its force to retain the lever 15 yieldably in closed position or in engagement with the upper face of the whiffletree, the members 28¹ and 28² enabling the tension of the spring to be controlled. Pivoted at 29 to the lever 25 is a stop rod 30 which extends through the guide aperture 20 21 of the plate 16 and likewise through a keeper 30¹ attached to the rear face of the member 12. By this simple means it will be obvious that when the plate 16 is in its rearward position with the stop member 30 25 engaging in the keeper 30¹ and the whiffletree 27 engaged by the stud 19 and the lug 26, the whiffletree will be retained in position relative to the cross bar 12, while at the same time free to oscillate in the ordinary manner under the influence of the "horse action" while at the same time the clips 15² hold the member 16 and its attachments from premature upward movement.

30 A pull device, such as a wire or cable 31, is connected at 32 to the releasing lever 25, and leads thence over a guide pulley 45 attached to the bracket to a point convenient to the driver upon the seat of the vehicle. 35 By this arrangement it will be obvious that so long as the horse is moving under normal conditions the whiffletree 27 will be held in oscillatory relation to the cross bar 12, and prevented from forward movement 40 through the coaction of the stud 19 lug 26 and stop member 30.

The improved device is simple in construction, can be inexpensively manufactured and applied without material structural change to the thill or tongue of the vehicle.

Having thus described the invention, what is claimed as new is:

1. A device of the class described comprising a guide member adapted to be attached to a whiffletree support, a bearing member slidable upon said guide member and provided with a stud with which the whiffletree is adapted to be detachably engaged, means adapted to hold the whiffletree in engagement with said stud and thereby lock the bearing member in withdrawn position, and means for releasing said holding

means to permit the overturning of the slideable member and its stud and the release of 65 the whiffletree.

2. The combination with a whiffletree and its support, of guide members attached to said support and each including a socket, a bearing member slidable upon said guide 70 members and having studs engaging in said sockets when the bearing member is overturned and another stud for engaging in the whiffletree, means for detachably engaging said bearing member to said support, and 75 means for releasing said bearing member engaging means.

3. The combination with a whiffletree and its support, of a bearing member detachably engaging said support and including a rearwardly extending guide loop, means for detachably engaging said whiffletree to said bearing member, a releasing device connected to said support, a holding member connected to said releasing device and extending through said guide loop and engaging said support, and means for actuating said releasing device to withdraw said holding member from said guide loop.

4. The combination with a whiffletree and its support, of a bearing member detachably engaging said support and including a rearwardly extending guide loop, means for detachably engaging said whiffletree to said bearing member, a releasing device connected to said support and including means for engaging said whiffletree, a holding member connected to said releasing device and extending through said guide loop and said support, and means for actuating said releasing device to simultaneously release said bearing member and whiffletree.

5. The combination with a whiffletree and its support, of guide members having sockets, a bearing member detachably engaging 105 said guide members and including a rearwardly extending guide loop and laterally directed studs to engage in said sockets when the bearing member is over-turned, means for detachably engaging said whiffletree to said bearing member, a releasing device connected to said support and including means for engaging said whiffletree, a holding member connected to said releasing device and extending through said guide 110 member and engaging said support, and means for actuating said releasing device to simultaneously release said whiffletree and bearing member.

In testimony whereof I affix my signature 120 in presence of two witnesses.

MARCUS A. JUAREZ. [L. s.]
